UNITED STATES PATENT OFFICE.

LUCIEN BORHAUER, OF CHICAGO, ILLINOIS, ASSIGNOR OF ONE-HALF TO JOSEPH H. HIRSCH, OF CHICAGO, ILLINOIS.

BED.

1,323,229.

Specification of Letters Patent.

Patented Nov. 25, 1919.

Application filed June 16, 1919. Serial No. 304,576.

To all whom it may concern:

Be it known that I, LUCIEN BORHAUER, a citizen of the United States of America, and a resident of Chicago, county of Cook, and

5 State of Illinois, have invented certain new and useful Improvements in Beds, of which the following is a specification.

The main objects of this invention are to provide a convertible twin bed device including 10 a pair of relatively movable bed frames capable of lateral adjustment to form a double-sized bed when occupying one position with respect to each other, and to form two single-size beds when occupying another 15 position with respect to each other; to provide improved track members for supporting said bed frames on a standard form of bedstead; to provide improved end members for slidably supporting said bed frames on said 20 track members; to provide improved means on said track members for retaining said bed frames in abutting relation; to provide an improved form of bracket on each end of said track members for retaining said bed 25 frames in spaced relation; and to provide improved means for adjustably supporting said track members on said bedstead.

An illustrative embodiment of this invention is shown in the accompanying drawings, in which—

Figure 1 is a plan of the improved bed structure as it appears when used as one double bed, the twin bed form being shown in dotted outline.

35 Fig. 2 is a side elevation of the same, the pillars of the bedstead being broken away.

Fig. 3 is a transverse sectional view taken on the line 3—3 of Fig. 1, part of the bedstead being broken away.

40 Fig. 4 is a view similar to Fig. 3, but showing the bed frames occupying the positions of twin beds.

Fig. 5 is a transverse section through one of the bed frames, showing one of the end 45 members thereof.

Fig. 6 is a bottom view of one of said end members.

Fig. 7 is a plan of one of the track members.

50 Fig. 8 is a side elevation of the same.

Fig. 9 is a sectional view taken on the line 9—9 of Fig. 8.

Fig. 10 is a perspective view of one of the reinforcing end brackets,

Fig. 11 is an elevation, partly broken 55 away, showing the manner of securing the device to the side panels of a wooden bedstead.

The improved form of bed shown in the drawings comprises a bedstead 1, a pair of 60 transversely disposed track members 2 adjustably mounted thereon, and a pair of individual bed frames 3 and 4 slidably supported on said track members so as to be adapted to be laterally shifted toward and away 65 from each other.

The bedstead 1 is of standard form having side rails or angle bars 5 and end rails 6 supported by the pillars 7.

The track members 2 are supported on the 70 side rails 5, one at each end of the bedstead and disposed transversely thereto. Each of said track members is of a length substantially equal to the distance between the side rails of the bedstead and is of inverted T- 75 shaped cross-section so as to provide a web 8 having a longitudinally extending shoulder 9 on each side thereof. The web 8 is cut away at the ends of the track members so as to form guideways 10, each of said guideways being of a length substantially equal to one-half the width of one of the bed frames. A pair of longitudinally disposed 80 slots 11 and 12 are formed in the web of each track member, and a pair of transversely 85 disposed grooves 13 and 14 are formed at respectively the inner and outer ends of each of the guideways 10, said grooves and slots all being disposed in substantially the same plane. A horizontally disposed recess 15 is 90 formed at each end of the track members 2 for engaging the horizontal leg of each of the angle bars 5, whereby the track members are adjustably supported on the bedstead.

In mounting the device on a bedstead having wooden side panels, it becomes necessary to bolt or otherwise secure angle irons on the inner faces of the side panels, as shown in Fig. 11. These angle irons may be of short lengths, one secured at each end of 100 the side panels.

A reinforcing end bracket 16 is rigidly secured to each end of the track members, said bracket being preferably cast to the form shown in Fig. 10. Each of the brackets 16 comprises a pair of flanges 17 disposed in substantially parallel spaced relation and integrally secured together at their 105

outer ends by a part 18 which serves as a stop to limit the outward movement of the bed frames. The brackets 16 are secured to the track members by rivets 19, said track members being formed and indented laterally at their ends so that the flanges 17 lie with their outer faces flush with the sides thereof, the flanges 9 and the outer parts of web 8 being cut away accordingly. Flanges 10 20 are formed on the brackets 16 at right angles to the flanges 17 and engage the lower surface of the track member 2 so as to reinforce the ends thereof and prevent any splitting by the rivets 19 when the members 2 are made of wood. The upper edges of the flanges 17 are recessed as at 21, adjacent the part 18 and in alignment with the grooves 14 so as to form continuations thereof. Shoulders 22 are formed on the sides 15 20 of the flanges 17 to strengthen the bracket and also to form continuations of the shoulders 9 of the track members. The depending parts 23 of the flanges 17 are spaced inwardly from the recesses 15 so as to allow 25 for the cutting of different sizes of recesses, depending upon the distance between the angle bars 5.

Each of the bed frames 3 and 4 comprises a bed spring 24 supported on a spring frame 30 35 25, said spring frame having a depending end member 26 secured to each end thereof. The end members at the foot and head of each bed spring are also connected by a pair of rods 27 disposed longitudinally beneath 35 said spring.

Each of the end members 26 comprises a channel-shaped member 28 having a supporting bracket 29 integrally formed at each end thereof, said bracket 29 being detachably secured to the spring frame 25 by bolts 40 45 30. The channel-shaped members 28 are adapted to straddle the webs 8 of the track members and are slideable thereon, each of said members comprising a pair of depending flanges 31 disposed in parallel spaced relation. A pair of bearing projections, preferably in the form of or including rollers 32 and 33, are supported in substantially the same horizontal plane between the 50 flanges of each channel member. The rollers are carried by pins 34 supported on the flanges 31 and secured against displacement by cotter pins 35. The rollers 32 are located adjacent the inner ends of the channel members and are slideable in the slots 11 and 12. The rollers 33 are located at substantially the center of the longitudinal axes of the bed frames and are slideable along the guideways 10.

When the bed frames 3 and 4 are in abutting relation, the rollers 32 are located at the inner ends of the slots 11 and 12, and the rollers 33 are seated in the grooves 13. When the bed frames are used as twin beds, 60 65 the rollers 32 are located at the outer ends

of the slots 11 and 12, and the rollers 33 are seated in the grooves 14. When the rollers 33 are seated in the grooves 13 or 14, the bed frames are thereby secured against any lateral shifting. To shift the bed frames from either of their locked positions it is necessary to raise the outer edges thereof sufficiently to disengage the rollers 33 from said grooves.

When the device is in twin bed form, the weight of each bed frame is evenly distributed or balanced over the angle bar upon which it rests, and so precludes the possibility of tilting when only one of the beds is used. Moreover, the overhanging side of a section in this position projects so little relative to the width and weight of the device as a whole, that there is no danger of tipping, even when one sits on the outer edge.

Although but one specific embodiment of this invention has been herein shown and described, it will be understood that numerous details of the construction shown may be altered or omitted without departing from the spirit of this invention as defined by the following claims.

I claim:

1. In a device of the class described, a bedstead, a transversely disposed track member supported thereon, a pair of bed frames, one of said bed frames being laterally shiftable toward and away from said other frame, said track member having a longitudinally disposed slot formed therein, a roller carried by said one frame and slideable in said slot, a guideway formed on said track member and extending inwardly from one end thereof, a roller carried by said one bed frame and slideable on said guideway, said guideway having a transversely disposed groove formed at the inner end thereof for receiving said last-mentioned roller, whereby said bed frames are retained in their abutting relation, said guideway having a transversely disposed groove formed at the outer end thereof for receiving said last-mentioned roller, whereby said bed frames are retained in their spaced relation.

2. In a device of the class described, a bedstead, a transversely disposed track member supported thereon, a pair of relatively shiftable bed frames slidably supported on said track member and adapted to be laterally shifted toward and away from each other, said track member having a pair of longitudinally disposed slots formed therein, bearings carried by said bed frames and slidably engaging said slots, guideways formed on said track member, bearings carried by said bed frames and slidably engaging said guideways, means at the inner ends of said guideways for receiving said last-mentioned bearings, whereby the opposed edges of said bed frames are retained in abutting relation, and means at the outer ends of said guide-

ways for receiving said last-mentioned bearings, whereby said opposed edges are retained in spaced relation.

3. In a device of the class described, a bedstead, a transversely disposed track member supported thereon, a pair of relatively shiftable bed frames slidably supported on said track member and adapted to be laterally shifted toward and away from each other, 5 said track member having a pair of longitudinally disposed slots formed therein, a pair of depending flanges mounted in spaced relation on each of said bed frames and straddling said track member, rollers carried by 10 said flanges adjacent the opposed edges of said bed frames and slidable in said slots, guideways formed on said track member and extending inwardly from the ends thereof, rollers carried by said flanges at substantially 15 the longitudinal axes of said bed frames and slidable on said guideways, said guideways having transversely disposed grooves formed at the inner ends thereof and adapted to receive said last-mentioned 20 rollers for retaining said bed frames in their substantially 25 longitudinally disposed slots formed therein, depending end members secured to each of said bed frames, rollers carried by said end members and slidable in said slots, guideways formed on said track member and extending inwardly from the ends thereof and adapted to receive said last-mentioned 30 rollers for retaining said bed frames in their spaced relation.

4. In a device of the class described, a bedstead, a pair of transversely disposed track members supported in substantially 35 parallel spaced relation on said bedstead, a pair of relatively shiftable bed frames slidably mounted on said track members and adapted to be laterally shifted toward and away from each other, said track members 40 having longitudinally disposed slots formed therein, depending end members secured to each of said bed frames, rollers carried by said end members and slidable in said slots, guideways formed on said track members 45 and extending inwardly from the ends thereof, rollers carried by said end members at substantially the longitudinal axes of said bed frames and slidable on said guideways, said guideways having transversely 50 disposed grooves formed at the inner ends thereof and adapted to receive said last-mentioned rollers for retaining said bed frames in spaced relation.

5. In a device of the class described, a bedstead, a pair of transversely disposed track members supported in substantially parallel 55 spaced relation on said bedstead, a pair of relatively shiftable bed frames slidably mounted on said track members and adapted 60 to be laterally shifted toward and away

from each other, said track members having longitudinally disposed slots formed therein, depending end members secured to each of said bed frames, rollers carried by said end members and slidable in said slots, guideways formed on said track members and extending inwardly from the ends thereof, rollers carried by said end members at substantially 70 the longitudinal axes of said bed frames and slidable on said guideways, said guideways having transversely disposed grooves formed at the inner ends thereof and adapted to receive said last-mentioned 75 rollers for retaining said bed frames in abutting relation, said guideways having transversely disposed grooves formed at the outer ends thereof and adapted to receive 80 said last-mentioned rollers for retaining said bed frames in spaced relation, the grooves and slots in each of said track members 85 being disposed in substantially the same horizontal plane.

6. In a device of the class described, a bedstead, a pair of transversely disposed track members adjustably supported in substantially parallel spaced relation on said bedstead, a pair of relatively shiftable bed frames slidably mounted on said track members and adapted to be laterally shifted toward and away from each other, said 90 track members having longitudinally disposed slots formed therein, depending end members secured to each of said bed frames, rollers carried by said end members and slidable in said slots, guideways formed on 95 said track members and extending inwardly from the ends thereof, rollers carried by said end members at substantially the longitudinal axes of said bed frames and slidable on said guideways, said guideways having transversely disposed grooves formed at the inner ends thereof and adapted to receive 100 said last-mentioned rollers for retaining said bed frames in abutting relation, said guideways having transversely disposed 105 grooves formed at the outer ends thereof and adapted to receive said last-mentioned rollers for retaining said bed frames in spaced relation.

7. A bedstead having inwardly disposed 110 horizontal supporting means on its side rails, in combination with track members provided with horizontal end grooves adapted to freely receive said supporting means, and each track-end having a reinforcing bracket secured thereto formed with an inward part embracing the corresponding track member back of its groove, and said brackets each having a forward 115 part of shoulder-stop character overlying the adjacent grooved part.

8. A bedstead having inwardly disposed horizontal supporting means on its side rails, in combination with track members provided with horizontal end 120 grooves

adapted to freely receive said supporting means, and each track-end having a reinforcing bracket secured thereto formed with an inward part embracing the corresponding track member back of its groove, and said brackets each having a forward part of shoulder-stop character overlying the adjacent grooved part, said brackets each including side walls set flush with the sides 10 of their rails and level therewith at the top, except that the outermost part of each bracket is formed to arrest movement on the rail.

9. In a device of the class described, a bed-
15 stead, a transversely disposed horizontal track member supported thereon, a pair of relatively shiftable bed frames slidably sup-

ported on said track member and adapted to be laterally shifted toward and away from each other, said track member having a pair 20 a longitudinally disposed slots formed therein near its center, bearings on said bed frames adjacent to their inner edges adapted to slidably engage said slots to prevent upward tilting of the inner edges of said frames, 25 means on said track member to retain said bed frames in abutting relation to form a double-sized bed, and means on said track member to retain said bed frames in spaced relation to form a pair of single-sized beds. 30

Signed at Chicago this 11 day of June, 1919.

LUCIEN BORHAUER.
